BANK SCREEN LIGHTING DEVICE

Filed June 19, 1923.

3 Sheets-Sheet 2

in a manner hereinafter described when it is desired to obtain access to the interior of the fixture.

At the interior of the fixture, and at suitable points at spaced intervals throughout the length thereof, is a combined mullion and wiring box 17. This element is of substantially rectangular formation, and is in the form of a frame, one or more of these mullions being employed in accordance with the length of the fixture, and each being designed to brace the fixture and to afford proper support for the front and rear walls 10 and 11. As seen in Figure 6, the base of the element 17 has a transversely extending bead 18 formed thereon, the edges of the base at opposite sides of said bead forming seats to support the contiguous ends of the glass panels 16. At the upper end of the element 17 is a boxlike receptacle 19, which constitutes a wiring box. The opposite walls of the receptacle 19 are provided with aligned openings 20 at the exterior of each of which is arranged a hublike flange 21. The openings 20 receive the bases of oppositely projecting insulated lamp sockets 22 which seat against said flanges 21, and are suitably secured in these openings to support the necessary lamps for giving the requisite illumination to the fixture. To each of the sockets 22 there is suitably connected a supporting frame 23 for reflectors for the several lamps, said frames 23 being provided with slotted attaching ears 24 which co-operate with fastening screws 25 through the medium of which the sockets 22 and the frames 23 are secured to the flanges 21.

The opposite sides of the walls of the receptacles 19, at the end portions thereof, are provided with oppositely disposed attaching lugs 26, said lugs 26 each being provided with an elongated slot 27 for receiving fastening screws 28, and the horizontal flanges of the rectangular offsets 12 of the front and rear walls 10 and 11 seat upon said lugs 26 and are secured thereto by the bolts 28. Obviously, the slots 27 afford adjustment of the bolts 28 to provide for adjustment of the side walls 10 and 11 in relation to the element 17.

The upper edges of the walls of the receptacle 19 are also provided with aligned notches 29 into which are fitted the ends of flanged wireways or troughs 30 wherein are positioned the electrical conductors included in the wiring connections of the fixture. While affording access to the wiring connections from the top of the fixture, the wireways 30 conceal these connections at the interior of the fixture, so that the wiring connections are not exposed at such interior.

Each side wall of the receptacle 19 has a vertical rib 31 at its exterior, and to each of said ribs 31 is connected a fastening screw 32 which penetrates a cover plate 33 through the medium of which the top of the fixture

is closed. This cover plate 33 has depending marginal flanges 34 which fit over the upwardly extending flanges 14 of the front and rear walls 10 and 11, thereby presenting a finished joint at these points, and effectually concealing the flanges 14 from view. Obviously, the plate 33 covers the wireways 30, so that access to the interior of these wireways cannot be had except upon removal of the cover plate 33. 75

Within the receptacle 19 is located also a suitable switching device 35. This may be of the pull chain type, or it may be of any other approved construction. This switching device controls the wiring connections 80 for switching on and off the several lamps connected to the various sockets 22.

At the terminal portions of the fixture are located end caps 36. These caps also are of paneled formation to impart an ornate appearance to the ends of the fixture, and the sides and bottom of said caps 36 are provided with inwardly extending flanges 37. At each corner of each of the caps 36 is a rectangular offset socket 38 wherein the upper and lower offsets 12 and 13 of the front and rear walls 10 and 11 are seated. This is clearly illustrated in Figures 4 and 7. Within the lower sockets 38 are provided inwardly extending anchoring lugs 39 between which and the walls of the sockets 38 the offsets 13 snugly fit, while the upper sockets 38 are likewise provided with inwardly extending flanges 40 between which and the walls of the upper sockets 38 the offsets 12 are snugly fitted and 90 anchored. By the connections just described the end caps 36 find frictional engagement with the front and rear walls 10 and 11, but to secure the latter permanently to the end caps 36 bolts 41 are provided. 95

The head of each of the upper sockets 38 is also grooved, as at 42, for the reception of the upwardly extending flanges 14 of the front and rear walls 10 and 11, whereby a further interlocking engagement of the walls 10 and 11 with the end caps is effected. 100

At the inner side of the head of each of the end caps 36 is located a boxlike receptacle 43, said receptacle constituting a wiring box, and the inner wall thereof has an opening 44 therein which is surrounded by a hublike flange 45. The opening 44 receives one of the insulated lamp bases 22, previously described and secured thereto also in the manner hereinbefore set forth. At the upper edge 115 of said inner wall of the receptacle 43 there is also provided flanged notches 46. Where only one wireway 30 is employed, as illustrated in Figures 4, 7 and 8, one of the flanged notches 46 receives the end of that wireway, 120 thus affording communication between the interior of the receptacle 43 and the wireway 30. In such event the other flanged notch 46 is closed by the displaceable closure web 47 which is seated in a groove 48, one of these 130

grooves being formed in each of the flanged notches 46. By the provision of said notches 46 either of the same may be selected for locating the wireway 30 at either the front or the rear of the fixture, or both of the same may be utilized, if it be desired to employ wiring connections for which one of the wireways is not sufficient.

At the exterior of the inner wall of the receptacle 48 is positioned a vertical rib 49 to which one of the fastening screws 32 is connected, thus providing means at the terminal portions of the fixture for holding the covering plate 33 in fixed relation to the end caps.

At the lower face of the base of the combined mullion and wiring box 17 is provided a pair of grooves 50 into which the flanges 15 of the walls 10 and 11 are designed to fit so as to afford further anchorage of these walls with respect to the element 17.

It will be noted that the glass panels 16 are of greater width than the opening between the flanges 15 in order to overhang these flanges and be supported thereby, and the ends of the panels 16 which lie contiguous to the end caps 36 rest upon the bottom flanges 37 of these caps. If it be desired to gain access to the interior of the fixture such may be easily accomplished by slightly elevating the end of the panel which lies adjacent to the bead 18 of the combined mullion and wiring box, whereupon the panel may be moved over the bead, as illustrated by dotted lines in Figure 2. This permits access to the interior of the fixture for such purposes as may arise, as for re-lamping the fixture.

In the use of the herein described fixture the same may be supported from the bank screen by any suitable means which will elevate the fixture above the working plane of the desk or desks to be illuminated. The glass panels 16 afford a diffused light which is directed immediately upon such working plane. Direct illumination thus is afforded. But in some circumstances it may be desirable for utilizing the fixture for indirect illumination, in which event as shown in Figure 9, the cover plate 33^a may be provided with openings 51 at suitable points so that the rays of light from the lamps opposite these openings may pass out through the latter. In such construction the reflectors 52 will be turned so as to direct the rays of light upwardly rather than downwardly, and this arrangement may be followed so that alternate lamps with their reflectors will project their rays through the top of the fixture, while the others project their rays downwardly through the glass panels 16^a.

The herein described invention provides a fixture of sectional character which may be readily assembled, the parts being so organized and inter-related as to permit their fitting together with ease and minimum expense, and their production by instrumental-

ties and methods of manufacture entailing but little labor in such production.

I claim:

1. A fixture of the class described, comprising front and rear walls, end caps into which said front and rear walls are fitted, the lower edges of the front and rear walls affording an opening at the bottom of the fixture, light-transmitting panels arranged at said opening for closing the same, a mullion arranged intermediate the end caps and affording support for the front and rear walls intermediate of the end caps, the adjacent ends of the light-transmitting panels being supported by said mullion, and illuminating units within the fixture.

2. A fixture of the class described, comprising front and rear walls, end caps into which said front and rear walls are fitted, the lower edges of the front and rear walls affording an opening at the bottom of the fixture, light-transmitting panels arranged at said opening for closing the same, the upper edges of the front and rear walls also affording an opening at the top thereof, a top arranged at the upper opening and closing the latter, a mullion arranged intermediate the end caps and affording support for the front and rear walls and said top intermediate of the end caps, and illuminating units within the fixture.

3. A fixture of the class described, comprising front and rear walls, terminal closures at the ends of said front and rear walls, the lower edges of the front and rear walls affording an opening at the bottom of the fixture, the upper edges of the front and rear walls also affording an opening at the top thereof, a top arranged at the upper opening and closing the latter, a mullion arranged intermediate the end caps and affording support for the front and rear walls and said top intermediate of the end caps, a wireway supported by said mullion and covered by said top, and illuminating units within the fixture.

4. A fixture of the class described, comprising front and rear walls, terminal closures at the ends of said front and rear walls, the lower edges of the front and rear walls affording an opening at the bottom of the fixture, a mullion arranged intermediate the end caps and affording support for the front and rear walls intermediate of the terminal closures, a wiring box associated with said mullion, a wireway supported by said mullion and in communication with said wiring box, and illuminating units within the fixture.

5. A fixture of the class described, comprising front and rear walls, terminal closures at the ends of said front and rear walls, the lower edges of the front and rear walls affording an opening at the bottom of the fixture, a mullion arranged intermediate the terminal closures and affording support for the front and rear walls intermediate of the terminal closures,

- front and rear walls along the lower mouldings being inwardly flanged at the bottom of the lower mouldings and affording an opening therebetween at the bottom of the fixture, a closure for the bottom opening resting on the inwardly flanged portions of the front and rear walls, the upper edges of the front and rear walls along the upper mouldings also being inwardly flanged as a part of those mouldings and also affording an opening therebetween at the top of the fixture, a closure for the top opening resting on the inwardly flanged portions of the front and rear walls, and illuminating units within the fixture.
16. A fixture of the class described, comprising separate front and rear walls ar-
- ranged in spaced parallel relation, flanged end caps into which the ends of said front and rear walls are fitted, means carried by the flanges on the end caps for holding the front and rear walls against withdrawal relative to the same, the lower edges of the front and rear walls affording an opening at the bottom of the fixture and being provided with panel-supporting means, a light-transmitting panel arranged at said opening and supported by said means for closing the opening, a top on the fixture, and illuminating units within the fixture.
- 30

In testimony whereof I have hereunto subscribed my name.

PAUL M. HOTCHKIN.
